UNITED STATES PATENT OFFICE.

CHARLES HARVEY, OF SOMERVILLE, MASSACHUSETTS.

OIL VAPORIZER AND BURNER.

1,317,289.

Specification of Letters Patent. Patented Sept. 30, 1919.

Application filed February 15, 1919. Serial No. 277,182.

To all whom it may concern:

Be it known that I, CHARLES HARVEY, a citizen of the United States, residing at Somerville, in the county of Middlesex and State of Massachusetts, have invented new and useful Improvements in Oil Vaporizers and Burners, of which the following is a specification.

This invention relates to a liquid fuel burner having a base adapted to be located in a fire-box and on the usual grate thereof, the burner including a retort receiving fuel oil which is converted into vapor in the retort, a vapor conduit having a vapor outlet 10 whereat the vapor is ignited, and a flame deflector which causes the flame to impinge upon the external surface of the retort.

The invention is embodied in the improvements hereinafter described and claimed.

20 Of the accompanying drawings forming a part of this specification,

Figure 1 is a top plan view of a burner embodying the invention.

Fig. 2 is a section on line 2—2 of Fig. 1.

25 Fig. 3 is a section on line 3—3 of Fig. 1.

Fig. 4 is a fragmentary top plan view illustrating a modification.

Fig. 5 is a section on line 5—5 of Fig. 4.

Fig. 6 is a section on line 6—6 of Fig. 4.

30 Fig. 7 is a top plan view illustrating another embodiment of the invention.

Fig. 8 is a section on line 8—8 of Fig. 7.

Fig. 9 is a perspective view of one of the struts shown by Figs. 7 and 8.

35 The same reference characters indicate the same parts in all of the figures.

In the drawings, 12 represents a base formed to be supported by the grate of a fire-box in a stove or furnace, the base being

40 provided with an upstanding wall or curb, forming with the base a pan adapted to receive a charge of oil for preliminary heating. 13 represents an oil conduit extending through and above the base, and adapted

45 at its lower end to be connected by another conduit member with an oil reservoir located at an elevated point. 14 represents a substantially continuous tubular retort surrounding a central space above the base, and supported in a plane substantially parallel with the plane of the base. The bore

50 15 of the retort has an intake end 16 communicating with the oil conduit 13, and an outlet end 17 communicating with the vapor conduit hereinafter described, said intake

and outlet ends being located near each other and at one side of the space surrounded by the retort. 18 represents an elbow-shaped vapor conduit, the upright portion of which communicates with the outlet 17. The horizontal portion of the vapor conduit extends over a portion of the base, and is supported above the bottom of the base by a seat 19 formed on the base. In the said horizontal portion is formed a vapor outlet 20 whereat the vapor is ignited, the said outlet 20 being arranged to project a flame upwardly into the center of the space surrounded by the retort 14.

21 represents a circular flame deflector, supported in the space surrounded by the retort, the circular margin of the deflector being substantially parallel with the retort. The deflector is adapted to project the flame radially against substantially all parts of the inner surface of the retort, the deflector being preferably constructed as shown by Figs. 2 and 3, and including a disk-shaped top portion which changes the course of the upwardly directed flame, an annular flange 22 depending from the top and provided with numerous perforations or small orifices 23, adapted to subdivide the flame into a multiplicity of small jets, and to project said jets radially against the inner surface 24 of the retort, and a bottom plate 24 on the lower edge of the flange 22, having a central opening which conducts the flame into the chamber formed by the said top, flange, and bottom plate.

25 The deflector is preferably provided with a flame conduit 26, which enters the opening in the bottom plate and depends from said plate, the intake end of the flame conduit being located over the vapor outlet 20.

30 The base 12 is provided at opposite sides of the seat 19 with air conduits 28 extending through and above the base, and arranged to conduct air into the intake end of the flame conduit 26, said intake end being preferably enlarged or bell-shaped, as shown by Figs. 2 and 3.

35 The flame deflector is preferably supported removably by means of an elbow-shaped arm 30, attached at one end to the base, its horizontal end portion overhanging a portion of the retort, and an ear 31 formed on the deflector and having an opening 32, which permits the ear to be placed on the arm 30, as indicated by Figs. 1, 2 and 3. The

ear opening 32 is of sufficient size to permit the ear to be slipped on to and off from the arm 30, the upper side of said arm being preferably provided with a notch at 33 (Fig. 2) formed to engage the upper side of the opening 32 and prevent accidental movement of the ear on the arm. Provision is therefore made for conveniently displacing the deflector and permitting access to the vapor conduit 18 and the vapor outlet 20 therein.

To reduce the temperature of the flame deflector, and thus prevent deposits of carbon therein, I make the arm 30 tubular, to form an air duct 35 extending through the base and through the entire length of the arm 30, so that air passes upwardly from below the base through the arm to conduct heat from the ear 31 and the flame deflector.

The retort is supported in part by the oil conduit 13, which is located at one side of the space surrounded by the retort, and in part by a strut 36 interposed between the retort and the base, and located at the opposite side of said base, provision being thus made for preventing the displacement of the retort by warping.

The retort as shown in Figs. 1 and 2, is formed as a continuous annulus having an enlargement 37 in which the intake end 16 and outlet end 17 are formed, the retort thus constructed being adapted to be formed as a casting. The retort may be formed by bending a length of wrought metal tubing, the intake end 16^a being at one end of the tube, and the outlet end 17^a being at the opposite end. The intake end may be connected with the oil conduit 13 by an elbow 38, and the outlet end may be connected with the vapor conduit 18 by an elbow 39, as indicated by Figs. 4, 5, and 6.

The described structure may be duplicated on a single base formed as indicated by Figs. 1 and 2, to support two vaporizing burners of the above-described construction.

In starting the operation of the burner, a limited charge of oil is supplied to the pan-shaped base, and ignited, a charge of oil being at the same time admitted to the retort, the supply to the retort being then shut off. When the oil burning on the base has sufficiently heated the retort to vaporize the oil therein, the vapor is ignited at the outlet 20, and the resulting flame is projected as above described against the retort. When the operation is sufficiently started, the supply connection to the retort is opened and the burner thereafter operates continuously.

The retort may be made of two horizontal sections 14^a and 14^b, as shown by Figs. 7 and 8, arranged in parallel planes, the sections 14^a being provided with the intake 16^b, having an enlargement 16^c, while the section 14^b is provided with the outlet 17^b, having an enlargement 17^c, said intake and outlet being connected, respectively, with the oil con-

duit 13 and the vapor conduit 18. The two sections are spaced apart to permit the passage of flame between them and are connected at 41 by a suitable connecting member, or vapor conduit, as shown by Fig. 8. The deflector is arranged to discharge jets of flame simultaneously on and between the two sections.

The flange 22 of the deflector is arranged in a horizontal plane which is parallel with the planes of the sections 14^a and 14^b. In consequence of the arrangement of the retort sections and the deflector flange in parallel planes, the jets of flame delivered by the outlets 23 are projected uniformly against the inner sides of the two sections and through the space between the sections. The retort is, therefore, more efficiently and uniformly heated than it would be if composed of a single helically coiled tube, the convolutions of which are in contact with each other, and are inclined relatively to the plane of the flange of the flame deflector.

The sections may be of substantially rectangular form, as shown by Fig. 7, and the deflector may be either circular, as shown by Fig. 1, or of rectangular form, with sides substantially parallel with the inner sides of the retorts.

The sections may be supported by a strut 36^a (Fig. 9), suitably secured to the base and provided with ears 36^b, one projecting over the upper section, another projecting between the two sections, and the third projecting below the lower section.

The term retort as used in the first two of the following claims is intended to mean either a single retort having its intake and outlet ends at the same height, as shown by Figs. 1, 2 and 3, or a retort composed of sections connected by a vapor-conducting connection 41, and having intake and outlet ends located at different heights, as shown by Figs. 7 and 8. Each form of retort may be either of substantially circular or annular form, as shown by Fig. 1, or of substantially rectangular form, as shown by Fig. 7.

It will be seen that in each embodiment of the invention, the intake and discharge ends of the conduit are provided with coupling members formed by the internally threaded portions of the enlargement 37 (Fig. 1), the internally threaded portions of the elbows 38 and 39, (Figs. 5 and 6), and the internally threaded portions of the enlargements 16^c and 17^c (Fig. 8). One of said coupling members detachably engages a complementary coupling member formed by an external screw thread on the oil conduit 13, and the other detachably engages a complementary coupling member formed by an external screw thread on the vapor conduit 18. In each embodiment the supporting strut 36 (Fig. 2), or 36^a (Fig. 8), is detachably connected with the retort. Provision is there-

fore made for locating the retort and maintaining it in its predetermined location by the oil conduit and the strut, and for confining the vapor conduit in its operative position by the retort and by the seat 19 on the base.

I claim:

1. An oil vaporizing and burning structure comprising a base, an upright oil conduit secured to and extending above the base near one end thereof, a substantially continuous tubular retort surrounding a central space above the base, and having intake and discharge ends located near each other at one side of said space, the said oil conduit communicating with the intake end and constituting a retort support, a vapor conduit communicating with the discharge end, and including an upright portion extending downwardly from the retort, and a horizontal portion extending over a portion of the base, said horizontal portion having a vapor outlet centrally located under said space, a seat on the base supporting the said horizontal portion, a retort-supporting strut interposed between the base and the portion of the retort opposite that supported by the oil conduit, and a flame deflector independently supported at the center of said space, and adapted to deflect flame from the vapor conduit radially against the retort, said structure being characterized first, by the fact that said intake and discharge ends of the retort are provided with coupling means, one of which detachably engages a complementary coupling means on the oil conduit, and the other a complementary coupling means on the vapor conduit; secondly, by the fact that said strut is detachably engaged with the retort, and also, by the vapor conduit seat, the retort being located and maintained in its predetermined location by the oil conduit and strut, and the vapor conduit being located and maintained in its operative position by the retort and seat.
2. An oil vaporizer and burner comprising a base, an oil conduit extending above the base, a substantially continuous tubular retort surrounding a central space above the base, and having intake and discharge ends located near each other at one side of said space, the intake end communicating with the oil conduit, a vapor conduit communicating with said outlet end and extending downwardly from the retort, and horizontally over a portion of the base, said vapor conduit having a vapor outlet centrally located under said space, and a flame deflector supported in said space and adapted to deflect flame radially against the inner surface of the retort,

the base being provided with an elbow-shaped arm overhanging a portion of the retort, and the flame deflector being provided with an apertured ear removably mounted on said arm, said arm being tubular and adapted to conduct air through the base and ear.

3. An oil vaporizer and burner comprising a base, a substantially continuous tubular retort surrounding a central space above the base and composed of two spaced apart horizontal sections arranged in parallel planes, one having an intake end and the other an outlet end, said intake and outlet ends being located near each other at one side of said space, and a vapor-conduit connecting said sections at the opposite side of said space, an oil conduit communicating with said intake end, a vapor conduit communicating with said outlet end and extending over a portion of the base, said vapor conduit having a vapor outlet centrally located under said space, and a flame deflector supported in said space and having a top adapted to change the course of an upwardly directed flame, and a flange depending from the said top, and arranged in a plane parallel with the planes of said sections, said flange being provided with flame outlets adapted to project jets of flame uniformly against the inner sides of the two sections and through the space therebetween.

4. An oil vaporizing and burning structure comprising a base, an upright support secured to and extending above the base near one end thereof, a substantially continuous tubular retort surrounding the central space above the base, and having intake and discharge ends located near each other at one side of said space, means being provided for admitting oil to said intake end, a vapor conduit communicating with the discharge end and including an upright portion extending downwardly from the retort, and a horizontal portion extending over the portion of the base, said horizontal portion having a vapor outlet centrally located under said space, a seat on the base supporting the said horizontal portion, a retort-supporting strut interposed between the base and the portion of the retort opposite that supported by the first-mentioned support, and a flame deflector independently supported at the center of said space, and adapted to deflect the flame from the vapor conduit radially against the retort.

In testimony whereof I have affixed my signature.

CHARLES HARVEY.
